ATTORNEY

UNITED STATES PATENT OFFICE.

FRED F. MEIER, OF STANFORD, MONTANA.

PACKAGE-TIE.

1,283,252.

Specification of Letters Patent. Patented Oct. 29, 1918.

Application filed March 14, 1918. Serial No. 222,442.

To all whom it may concern:

Be it known that I, FRED F. MEIER, a citizen of the United States, residing at Stanford, in the county of Fergus and State of 5 Montana, have invented certain new and useful Improvements in Package-Ties, of which the following is a specification.

This invention relates to package ties and more particularly to an improved device for 10 engaging and securing the free ends of a fastening cord employed in tying a package.

The principal object of the invention is to provide a simple and strong device that may be readily formed from a single strip 15 of metal to provide the different elements for receiving loops formed in the binding cord to secure the latter in position without the necessity of tying knots.

A further object of the invention is the 20 provision of a package tie which consists of comparatively few parts and is simple in construction, but durable and well adapted to withstand the rough usage to which devices of this character are ordinarily subjected.

For a full description of the invention and the advantages and merits thereof, reference is to be had to the following description and accompanying drawings, in 30 which:—

Figure 1 is a perspective view of one form of the package tie constructed in accordance with my invention.

Fig. 2 is a perspective view of a modified 35 form of the invention, the cord receiving element being arranged at each end of the metal strip.

Fig. 3 is an enlarged plan view of one 40 end of the device illustrating the application of a binding cord thereto.

Referring to the drawings, and particularly to Figs. 1 and 3, it will be noted that the device is constructed from an elongated strip of metal having its longitudinal 45 marginal edges folded upon themselves to provide reinforcing strips for strengthening the strip of metal. One end of the strip is folded upon itself as indicated at 5 to form the retaining plate 6 and this plate overlies 50 the straight portion of the strip and is spaced therefrom to form the cord receiving space 7. This end of the strip is again bent upon itself and over the plate 6 as indicated at 8 and this folded portion is bent 55 diagonally so that the end of the strip pro-

jects over one side edge forming a tongue 9. This tongue 9 is spaced from the adjacent portion in order that the cord may be extended through the space beneath the tongue which is done as shown in Fig. 3. The end 60 of the cord A is first passed through the space 7 between the body of the strip and the plate 6, as indicated by dotted lines. The cord is then passed over the top of the plate 6, over its opposite edge and again 65 under the plate 6, from which point it is brought through the space between the plate 8 and the triangularly shaped member beneath the tongue 9. The diagonal edge is then engaged by the cord which 70 passes over and under the tongue 9 and is pulled through the space between the plate 6 and the triangular shaped member, so that the cross portion indicated at 10 binds the 75 cord and prevents accidental displacement.

From the foregoing it will be observed that a very simple and durable device has been provided, the details of which embody the preferred form. I desire it to be understood, that slight changes may be made in 80 the minor details of construction without departing from the spirit of the invention or scope of the claims hereunto appended.

I claim:

1. A package tie comprising a metallic 85 strip, a retaining plate formed at one end of the strip and overlying the same in spaced relation thereto to provide a cord receiving space, a tongue disposed above the said plate and projecting beyond one side edge thereof and a triangular portion formed between the said tongue and the said plate.

2. A package tie comprising a strip of flexible metallic material having one end folded upon itself and spaced from the body 90 of the strip to provide a cord receiving space, the end of the strip being then folded upon the said retaining plate and bent diagonally with respect to the said retaining plate to provide a diagonal edge, and a tongue formed by the end of the said plate projecting beyond the side edge of the said plate and in spaced relation from the adjacent portion of the said folded end.

3. A package tie comprising a metallic 105 strip having at one end a retaining plate disposed in spaced relation from the proximate surface of the body of the said plate, the said end of the strip being extended over the top of the said retaining plate and held 110

in spaced relation thereto, the said extended end portion being folded diagonally whereby the end of the said strip will extend beyond the edge of the said plate to form a 5 right angularly projecting tongue having a triangular shaped portion, the said tongue being spaced from the said triangular shaped portion of the folded end, each of

the said folded parts being spaced apart to provide space for receiving a cord. 10

In testimony whereof I affix my signature in presence of two witnesses.

FRED F. MEIER.
